UNITED STATES PATENT OFFICE

171,875

HANDBAG OR SIMILAR ARTICLE

Harry Ames, New York, N. Y.

Application November 2, 1953, Serial No. 27,415

Term of patent 7 years

(Cl. D87—3)

To all whom it may concern:

Be it known that I, Harry Ames, a citizen of the United States of America, residing in New York city, county of New York, and State of New York, have invented a new, original, and ornamental Design for a Handbag or Similar Article, of which the following is a specification, reference being had to the accompanying drawing, forming part thereof, wherein:

drawn to a smaller scale, with a portion of the handle removed for convenience of illustration.

I claim:

The ornamental design for a handbag or similar article, substantially as shown and described.
